UNITED STATES PATENT OFFICE

2,274,582

PROTRACTOR

Albert G. Bauer, Pontiac, Mich.

Application April 2, 1941, Serial No. 386,540

This invention relates to protractors of the pivoted arm type, and its general object is to provide a protractor in which the arm is normally held fixed relative to the protractor body against casual movement from any adjusted position, but can be instantly manually released from its held position to allow free adjustment merely by applying pressure to the body, and when the pressure is relieved, the arm becomes fixed, thus it will be seen that my protractor not only eliminates inaccuracies resulting from the arm creeping or becoming accidentally moved, but also the necessity of manipulating thumb screws or the like now in general use to hold the arm in adjusted positions.

A further object is to provide a protractor which is reversible or in other words either side can be used, and such coupled with the instantaneous releasable and automatic holding feature for the arm, materially expedites the use of the protractor.

Another object is to provide a protractor of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view of one side of one form of my protractor, the other side being identical, and the arm is illustrated in several of its adjusted positions, in fixed and dotted lines.

Figure 2 is an enlarged fragmentary sectional view taken approximately on line 2—2 of Figure 1, looking in the direction of the arrows.

Figure 3 is a sectional view taken approximately on line 3—3 of Figure 1, looking in the direction of the arrows.

Figure 4 is a perspective view of the spring strip of the form of Figure 1.

Figure 5 is a fragmentary side view of a modified form.

Figure 6 is a sectional view taken approximately on line 6—6 of Figure 5, looking in the direction of the arrows.

Referring to the drawing in detail, and particularly to the form of Figures 1 to 4, it will be

noted that the body of my protractor includes a pair of substantially identical plate sections 1 and 2, formed from sheet metal or any other material suitable for the purpose, and each section is provided with an elongated strip like base member 3 having a straight outer or lower edge. Formed on the inner edge of the base member adjacent the ends thereof are the ends of an arcuate member 4 having the usual numbered angle scale or degree graduations on the outer face thereof, and also formed on the upper edge of the base member centrally of its ends for disposal perpendicular to the inner edge, like the arcuate member 4 is an apertured ear 5. The outer ends of the base member 3 may be beveled or inclined for a portion of their length, and the inner or upper edge may likewise be inclined toward the lower edge from the arcuate member to the ear, as shown in Figure 1. However, the shape of those edges are not important as far as the invention is concerned, and they may be of any other desirable shape.

The sections 1 and 2 are connected together in spaced parallel relation, with the graduated faces of the arcuate members outermost, by a pair of flat headed rivets 6 that have their shanks extending through the base members 3 adjacent to the ends thereof, and while both sections may be loosely mounted on the rivets, at least the section 1 is loosely mounted to allow free tilting movement thereof toward and away from the section 2 for a purpose which will be later apparent. The rivet holes of the base member 3 of the section 1 are preferably elliptical shape, with their long axes disposed perpendicular to the outer edge of the base member to bring about the tilting movement set forth.

Mounted for swinging movement between the sections is a flat arm or blade 7 that is pivoted to and between the ears 5 of the sections, by a hollow headless pin 8 fixed in the arm and extending therethrough to provide bearings rotatably mounted in the apertures of the ears, as best shown in Figure 2, and the aperture of the ear of the section 1 is likewise elliptical in shape to allow for the tilting movement above referred to. While the entire portion of the arm that is disposed inwardly of the inner edge of the arcuate members 4 is reduced as at 9, the wide sides of the arm are further reduced to provide shoulders 10 that are curved to follow the curvature of the outer edges of the members 4 and are disposed in wiping engagement therewith, so that the latter edges and shoulders cooperate to guide the arm in its movement, as will be

apparent upon inspection of Figure 2. The corners of the shoulders are preferably cut away in beveled formation and the outer portion of the arm beyond the shoulders is of a width so that the wide faces of the arm are flush with or disposed in the same plane with the outer faces of the rivet heads for supporting the protractor in a level position, when in use, as will be apparent.

Disposed between the base members is a relatively thin resilient strip 11 formed from spring metal or the like and of a length to extend substantially to the ends of the base members, as shown in dotted lines in Figure 1. The strip is transversely curved in channel formation for the major portion of its width and throughout its length and the longitudinal edge portions from the inner wall of the channel are substantially flat and arranged in the same plane for bearing engagement with the base member of the plate 2, while the outer wall of the channel along its longitudinal center bears against the base member of the section 1, as clearly shown in Figure 2. The strip 11 has holes 12 therein adjacent its inner longitudinal edge, through which extends the shanks of the rivets 6, and a pair of holes 13 are arranged in the strip 11 at the longitudinal center thereof. Mounted within the holes 13 are teats 14 formed on the base member of the section 1 by indentations, and the holes 13 provide seats for the teats 14 for rocking movement therein, as will be apparent upon inspection of Figure 2.

From the foregoing, it will be seen that the spring strip 11 normally urges and holds the arcuate member of the section 1 in bearing engagement with the arm 7, so that both of the arcuate members cooperate to set up a clamping action against the arm to hold the latter against casual movement relative to the body and in any adjusted position in which it may be set. Such action is brought about due to the arrangement of the points of connection of the strip 11 to the rivets 6 and the points of connection of the strip with the teats, as by such arrangement, the rivets act as fulcrum means for the section 1 which is normally held in tilted position, with the arcuate member thereof bearing against the arm. It will be further obvious that when it is desired to release the arm to allow adjustment thereof, that the base member of the section 1 is pressed toward the base member of the section 2, and when the pressure is relieved, the section 1 will assume its normal clamping position.

In the form of Figures 5 and 6, I provide a strip 15 of rubber or like elastic material that is used in place of the metallic strip 11, and it will be noted that the rivets 16 extend through the strip 15 adjacent the inner longitudinal edge thereof, so that the major portion of the width of the strip 15 is free from its outer longitudinal edge, to exert an outward pressure against the base member 17 of the plate section 18, for urging and holding the arcuate member 19 thereof against the arm 20 to cooperate with the arcuate member of the plate section 21 to hold the arm 20 in adjusted positions. By that construction, it will be obvious that when pressure is applied to the base member 17, the arm is released to allow adjustment thereof. I provide three rivets 16 in this form, as shown in Figure 5, and the rivet holes of the base member 17 are elliptical shape to allow for the rocking movement of the plate section 18 relative to its companion plate section.

The remaining structure of the form of Figures 5 and 6 is identical to that of the other form, and the arms of both forms may have numbered linear graduations thereon, if desired, as well as a pointer line cooperating with the indicia graduations, as shown in Figure 1.

It is thought from the foregoing description that the advantages and novel features of the invention will be readily apparent.

It is to be understood that changes may be made in the construction and in the combination and arrangement of the several parts, provided that such changes fall within the scope of the appended claims.

15 What I claim is:

1. A protractor comprising a pair of spaced normally parallel sections, an arm pivotally mounted between the sections for adjustment relative thereto, means connecting the sections together for tilting movement of at least one section toward and away from the arm, and resilient means associated with the sections to bring about a clamping action thereof against the arm to hold the latter in adjusted positions.

2. A protractor comprising a pair of spaced normally parallel body sections, each including a base member, a graduated arcuate member formed on the base member, an arm pivotally mounted between the base members for adjustment relative to the arcuate members, means connecting the base members for tilting movement of at least one section toward and away from the arm, and resilient means secured between the base members by the connecting means

30 to bring about a clamping action of the arcuate members against the arm to hold the latter in adjusted positions.

3. A protractor comprising a pair of spaced normally parallel body sections formed from sheet material and each including an elongated base member, a graduated arcuate member having its ends formed on the base member, an ear formed on the base member, an arm extending between the sections and pivotally connected to the ears for adjustment of the arm relative to the arcuate members, said arm being shouldered and the shoulders being disposed in wiping engagement with the outer edges of the arcuate members to guide the arm in its movement, means connecting the base members together for tilting movement of one section toward and away from the arm, and a resilient strip substantially coextensive with the length

45 of the base members and secured between the latter by the connecting means thereof to normally urge the arcuate member of the tiltable section against the arm for cooperation with the arcuate member of the other section to set up a clamping engagement on the arm to hold the latter in adjusted positions.

4. A protractor comprising a pair of spaced normally parallel body sections formed from sheet material and each including an elongated base member, an arcuate member formed on the base member and having numbered degree graduations on one face thereof, an ear formed on the base member, an arm extending between the sections and pivotally connected to the ears for adjustment relative to the arcuate members, means connecting the base members together for tilting movement of one section toward and away from the arm, a resilient strip secured between the base members by the connecting means thereof and being channeled

along its longitudinal center, and the outer face of the wall of the channeled portion bearing against the base member of the tiltable section and the longitudinal edge portions of the strip bearing against the base member of the other section to urge the arcuate member of the tiltable section against the arm to cooperate with the arcuate member of the other section to set up a clamping engagement on the arm to hold the latter in adjusted positions.

5. A protractor comprising a pair of spaced normally parallel body sections, each including an elongated base member, a graduated arcuate member formed on the base member, an ear formed on the base member and extending centrally therefrom, an arm extending between the sections and pivotally connected to the ears for adjustment of the arm relative to the arcuate members, rivets connecting the base members together for tilting movement of one section toward and away from the arm, a resilient strip secured between the base members by the rivets and the latter extending through the strip adjacent to the inner longitudinal edge thereof, said strip being channeled along its longitudinal center and having flat longitudinal edge portions, the outer face of the wall of the channeled portion bearing against the base member of the tiltable section and the flat edge portions bearing against the base member of the other section to urge the arcuate member of the tiltable section against the arm to cooperate with the other arcuate member to set up a clamping engagement on the arm to hold the latter in adjusted positions, said strip being provided with holes at the longitudinal center of the channel, and teats on the base member of the tiltable section and mounted in the holes for rocking movement.

6. A protractor comprising a pair of spaced normally parallel body sections, each including a base member, a graduated arcuate member formed on the base member, an arm pivotally mounted between the base members for adjustment relative to the arcuate members, means connecting the base members for tilting movement of at least one section toward and away from the arm, and an elastic strip secured between the base members by the connecting means thereof with the latter extending through the strip adjacent to its inner longitudinal edge for the strip to bring about a clamping action of the arcuate members against the arm to hold the latter in adjusted positions.

7. A protractor comprising a pair of spaced normally parallel body sections formed from sheet metal and each including an elongated base member, a graduated arcuate member formed on the base member, an ear formed on the base member, an arm extending between the sections and pivotally connected to the ears for adjustment of the arm relative to the arcuate members, rivets connecting the base members together for tilting movement of one section toward and away from the arm, a rubber strip substantially coextensive with the length of the base members and secured between the latter by the rivets and said rivets extending through the strip adjacent to the inner longitudinal edge thereof for the portion of the strip outwardly of the rivets to normally urge the arcuate member of the tiltable section against the arm for cooperation with the arcuate member of the other section to set up a clamping engagement on the arm to hold the latter in adjusted positions.

ALBERT G. BAUER.
